UNITED STATES PATENT OFFICE.

WILLIAM J. MURRAY, OF DENVER, COLORADO.

COAL-SLACK LEVELING AND TAMPING APPLIANCE.

No. 826,184.

Specification of Letters Patent.

Patented July 17, 1906.

Application filed January 30, 1906. Serial No. 298,721.

To all whom it may concern:

Be it known that I, WILLIAM J. MURRAY, a citizen of the United States, residing at Denver, in the county of Denver and State of Colorado, have invented new and useful Improvements in Coal-Slack Leveling and Tamping Appliances, of which the following is a specification.

This invention relates to an appliance for leveling and tamping coal-slack in ovens of the so-called "beehive" type.

The nature of the invention will be readily comprehended, reference being had to the following detailed description of the construction and operation and to the accompanying drawings, illustrating the appliance in its preferred form of embodiment, it being understood that various changes and modifications may be made therein without exceeding the scope of the invention defined by the concluding claims.

In the drawings, Figure 1 is an elevation, partly in section, of a coal-slack leveling and tamping appliance embodying the invention. Fig. 2 is an enlarged detail view of certain combined parts or members of the appliance in one position. Fig. 3 is a view similar to Fig. 2 with the parts in another position. Figs. 4, 5, and 6 are further enlarged detail views of certain of the parts. Fig. 7 is a cross-sectional view of one of the tamping arms 23.

Referring to the drawings by numerals, 1 designates an oven of the so-called "beehive" type having an upper charging-opening 2. The coal-slack as it is fed into the oven through the opening 2 tends to the formation of a conical body, and it is the purpose of the present invention to expeditiously change such formation to obtain a leveled mass of slack and one which is tamped to the desired degree of compactness. To this end there is employed means, including a device operating in the manner hereinafter described, to gradually level and tamp the slack-body, the actions of the device being at all times under complete control of the operator.

In its preferred form the appliance consists of a ram having members capable of being folded and extended and connected to be vibrated from a suitable source of power. All of the parts of the appliance are supported on a wheeled carriage 3, traveling on rails 4 to bring the leveling and tamping device into and out of operative position over the oven-

opening 2. Vertically mounted in the carriage is a shaft 5, having a pointed lower end and a threaded portion 6 between unthreaded end portions 7 8. The upper end portion 6 of the shaft is slidable in an opening in a beveled gear-wheel 9, mounted horizontally in the carriage-frame and rotated by a beveled pinion 10 on a counter-shaft 11. 12 is an engine, the drive-shaft of which is connected 65 with the counter-shaft 11 by a belt and pulleys, as shown. The upper portion 7 of the shaft 5 is provided with a feather 13, whereby said shaft is rotated with the gear-wheel 9.

The shaft and parts carried thereby are lowered and raised into and out of operative position by a rope or cable 14, attached to the upper end of the shaft and passed around a sheave 15, mounted on the top of a derrick 16 erected on the carriage. In said vertical 75 movements the shaft slides freely in the gear-wheel opening, as will be understood. Loosely encircling the shaft 5 is a sleeve 17, having at its upper end a collar 18, provided with an annular groove 19 for a purpose 80 presently to be explained. Fixed on the lower end of the sleeve is a collar 20, having oppositely-projecting ears 21, to each of which is connected one end of a link 22, the other end of the link being connected to a 85 leveling and tamping arm or ram member 23, pivoted at its inner end to a head 24 on the lower end 8 of the shaft 5. Through the medium of the links 22, connecting the arms 23 and sleeve, the latter and shaft 5 rotate in 90 unison.

The sleeve and collar are vertically slidable on the shaft to obtain the folding and extension of the arms 23. To obtain such sliding movements, there is employed an 95 arm 25 having a threaded opening 26 engaging the threaded portion 6 of the shaft. The arm, to be readily connected and disconnected when required, is formed of two similar members pivotally connected together at 100 one end by a link 27 and detachably connected at the opposite end by a nut-equipped bolt 28. When in position, the arm 25 is in engagement with the collar 18 and is prevented from turning by a stationary guide- 105 rod 29, passing through an opening 30 between the arm members.

In operation the lower end of the shaft 5, with the arms 23 folded thereagainst, is brought by movement of the carriage in line 110 with the center of the oven-opening, and by slackening the rope or cable 14 is lowered into

the oven to the position shown in Fig. 2, penetrating the pile of material to the desired depth. The engine being set in motion, the shaft 5 is rotated through the described connections, and by the action of the rotating screw 6, the arm 25 being incapable of turning, is forced downwardly, moving the sleeve 17 and expanding or unfolding the arms 23. The arms coincident with the unfolding movement receive a rotary motion imparted to them by the revolving shaft, and the material acted upon by said arms is uniformly leveled, as indicated by the dotted line 31 in Fig. 1. The tamping action follows the leveling action above described. After the operation of the parts to obtain the limit of unfolding movement of the arms 23 the sleeve and shaft are locked together by tightening a screw 32, carried by the sleeve against the shaft, or, if preferred, by locking the collar 18 and arm 25 together, this being accomplished by bringing a hook 33, pivoted on the collar, into engagement with a pin 34 on the arm 25. The means for obtaining the tamping movement of the arms consists of a rod 35, vertically reciprocable in guides 36 and receiving motion from the cross-head or eccentric of the engine through an arm 37, adjustably connected through the medium of lock-nuts 38 39 with the upper end of the rod. The rod has at its lower end an arm 40, extending therefrom at a right angle and having a curved end 41, adapted as the arm is swung into place to enter the groove 19 in the collar 18 and be held therein by the hook 33, which drops in front of said end. With the parts in this position the shaft 5 is coupled to the engine, and the latter being set in motion the shaft 5 and arms are both rotated and vibrated and uniform tamping of the leveled material is obtained. To fold the arms 23 against the shaft end 8, the hook 33 is caused to engage the pin 34 on the arm 25, and the shaft being reversely rotated the sleeve is elevated and the arms brought into folded position, the appliance being thus in condition to be withdrawn and transferred to another oven for the next operation.

I claim as my invention—

- 50 1. In a coal-slack leveling and tamping appliance for beehive ovens and the like, a movable element, and leveling and tamping members carried by said element.
2. In a coal-slack leveling and tamping appliance for beehive ovens and the like, a movable element, and foldable and extensible leveling and tamping members carried by said element.
- 55 3. In a coal-slack leveling and tamping ap-

pliance for beehive ovens and the like, a shaft, 60 leveling and tamping members carried by said shaft, means for raising and lowering said shaft, and means for folding and extending said members.

4. In a coal-slack leveling and tamping appliance for beehive ovens and the like, a shaft carrying leveling and tamping means, mechanism for moving said means to obtain the leveling of the material, and mechanism for vibrating the shaft and means to obtain the tamping of the material. 65

5. In a coal-slack leveling and tamping appliance for beehive ovens and the like, a shaft carrying leveling and tamping means, a device for moving the shaft and means into and 75 out of the oven, mechanism for moving said means to obtain the leveling of the material, and mechanism for vibrating the shaft and means to obtain the tamping of the material.

6. In a coal-slack leveling and tamping appliance for beehive ovens and the like, a movable element, leveling and tamping members pivoted to said element, means for folding and unfolding said members, and means for 80 vibrating said element and members when 85 the latter are in unfolded condition.

7. In a coal-slack leveling and tamping appliance for beehive ovens and the like, a vertically-movable threaded shaft, means for rotating said shaft, leveling and tamping 90 members pivoted to said shaft to be folded and extended, a sleeve slideable on the shaft and having link connections with said members, and a threaded device in engagement with the shaft-threads and operated in the 95 rotation of the shaft to move the sleeve and obtain the folding and extension of said members.

8. In a coal-slack leveling and tamping appliance for beehive ovens and the like, a vertically-movable threaded shaft, means for 100 rotating said shaft, leveling and tamping members pivoted to said shaft to be folded and extended, a sleeve slideable on the shaft and having link connections with said members, a threaded device in engagement with the shaft-threads and operated in the rotation of the shaft to move the sleeve and obtain the folding and extension of said members, and a vibratory element adapted to be 105 detachably connected with said sleeve.

In testimony whereof I affix my signature in presence of two subscribing witnesses.

WILLIAM J. MURRAY.
